Int. Cl. D12—15

U.S. Cl. D12—143

FIG. 1 is a perspective view of a tire showing our new design, it being understood that the tread pattern is repeated throughout the circumference of the tire;

FIG. 2 is an end elevational view thereof; and

FIG. 3 is an enlarged fragmentary plan view of the tread pattern.

The broken line showing of the wheel in FIG. 1 is for illustrative purposes only.

We claim.

The new and ornamental design for a tire, substantially as shown and described.
